UNITED STATES PATENT OFFICE.

MORRIS L. RICH, OF PHILADELPHIA, PENNSYLVANIA.

COLLAR-FASTENER.

1,099,936.

Specification of Letters Patent. Patented June 16, 1914.

Application filed August 4, 1911. Serial No. 642,242.

To all whom it may concern:

Be it known that I, MORRIS L. RICH, a citizen of the United States, residing at Philadelphia, in the county of Philadelphia and State of Pennsylvania, have invented 5 certain new and useful Improvements in Collar-Fasteners, of which the following is a specification.

My invention relates to improvements in 10 collar fasteners, the object of the invention being to provide a collar fastener which is especially adapted for use at the back and in the neck band of the shirt to securely hold the collar at the back, and enable the 15 collar to be readily attached and detached, and when attached will be held against any possibility of riding upward on the collar band.

A further object is to provide a collar 20 fastener of this character which is composed of a single piece of metal or other suitable material, and which will be comfortable to the wearer, as well as efficacious in use.

With these and other objects in view, the 25 invention consists in certain novel features of construction and combinations and arrangements of parts, as will be more fully hereinafter described and pointed out in the claim.

30 In the accompanying drawings: Figure 1, is a view in elevation partly broken away illustrating the back of a collar secured to a neck band by means of my improved fastener. Fig. 2, is a view in vertical section 35 through the collar, fastener, and shirt, and Fig. 3, is a perspective view of my improved fastener.

1, represents a shirt and 2 a neck band thereon, which is provided with the ordinary 40 downwardly projecting outer fold 3, and this outer fold has the ordinary button hole 4.

5, is the ordinary turn-over collar, which is provided with the ordinary button hole 6 45 at the back.

My improved fastener comprises two integral parts, namely, a body portion 7, and a tongue 8. Body portion 7 is curved longitudinally so as to conform to the shape 50 of the neck band of the shirt when in use, and lie smoothly under the outer fold 3 and be hid thereby. The tongue portion 8, which is integral with the body portion 7,

projects outwardly and downwardly from the center and lower edge of said body portion forming a ledge 9, and said tongue then curves sharply downwardly and outwardly as shown at 10. The tongue preferably reduces in width from its attached to its free end, and flares outwardly and is rounded at 60 its free end as shown at 11 to readily enter the button hole 6 of the collar.

In operation, the body portion 7 is interposed between the neck band and the over turned fold 3, and the tongue 8 is projected 65 through the button hole 4. When it is desired to fasten the collar 5, it is simply necessary to position the button hole 6 of the collar over the free end of tongue 8, and then draw the collar upwardly until the 70 ledge portion 9 of the tongue is projected through the button hole 6. This ledge portion serves to hold the collar against downward movement, and the lower free portion of the tongue prevents any possibility of 75 the collar moving upwardly. Such a construction renders it easy to fasten a collar which is highly starched, as it requires little force to compel the tongue to enter an ordinary button hole, and when in use, the device 80 will be comfortable to the wearer as it conforms to the shape of the collar band, and does not press against the neck of the wearer.

Various slight changes might be made in 85 the general form and arrangement of parts described without departing from my invention, and hence I do not limit myself to the precise details set forth, but consider myself at liberty to make such changes and 90 alterations as fairly fall within the spirit and scope of the appended claim.

Having thus described my invention, what I claim as new and desire to secure by Letters Patent is:

A device adapted to be inserted in the rear collar button-hole of a two fold shirt band, comprising a laterally extending relatively narrow body portion, and a collar attaching tongue projecting downwardly from 100 the lower edge of the body portion, the lower edge of the body portion extending laterally in both directions from the base of the tongue to provide shoulders on which the device may be turned in the shirt band 105 pocket in the process of insertion, and the

upper edge of said body portion being perpendicular to the longitudinal axis of the button so as to present an elongated supporting edge, which is adapted to lie adjacent the fold in the shirt band, whereby tilting of the button in the button-hole is prevented.

In testimony whereof I have signed my name to this specification in the presence of two subscribing witnesses.

MORRIS L. RICH.
